UNITED STATES PATENT OFFICE.

REUBEN B. BENJAMIN, OF CHICAGO, AND PAUL D. PHILLIPS, OF ELMHURST, ILLINOIS,
ASSIGNORS TO BENJAMIN ELECTRIC MANUFACTURING COMPANY, OF CHICAGO,
ILLINOIS, A CORPORATION OF ILLINOIS.

ELECTRIC-LAMP SOCKET.

Application filed April 21, 1920. Serial No. 375,484.

To all whom it may concern:

Be it known that we, REUBEN B. BENJAMIN, a citizen of the United States, residing at Chicago, in the county of Cook and State of Illinois, and PAUL D. PHILLIPS, a citizen of the United States, residing at Elmhurst, in the county of Du Page and State of Illinois, have invented certain new and useful Improvements in Electric-Lamp Sockets, of which the following is a full, clear, concise, and exact description, reference being had to the accompanying drawings, forming a part of this specification.

This invention relates to electric lamp sockets of the type designed to lock the lamp against surreptitious removal, and it relates further to improved means for effecting authorized unlocking of the lamp.

One object of this invention is to provide improved locking means in connection with an electric lamp socket whereby, upon application of the lamp to the socket, the same will be simultaneously locked therein.

Another object is to provide improved detachable unlocking means to retract said locking means and make possible the removal of the lamp.

Other objects will appear hereinafter.

In the drawings:

Fig. 1 is a vertical sectional view of a lamp socket;

Fig. 2 is a vertical side elevation of the invention, with the porcelain parts removed;

Fig. 3 is a detail view looking at the bottom of Fig. 2;

Fig. 4 is a detail sectional view looking at the side of Fig. 2; and

Fig. 5 is a detail sectional view on the line 5—5 of Fig. 4.

In the construction shown, we provide an electric lamp socket comprising the conventional type of base 10 of porcelain or other insulating material, the same having

a cap 11 of the same material suitably connected thereto. A center contact 12 is mounted on said cap member 11 for engagement with a suitable translating device.

The base 10 has a conducting plate 13 suitably connected thereto by means of screws 14. A conducting member 15 is positioned on said plate and extends upwardly into the cap 11. Said plate is apertured sub-

stantially centrally thereof to accommodate a threaded shell contact 16.

55

The locking device, as shown in this construction, comprises a dog 17, disposed in a slot 18 formed in the end of a stud 18', said stud 18' having a threaded cylindrically formed end 19, as seen in Figs. 1, 4 and 5.

60

Mounted below the plate 13, and secured thereto by means of the screws 14, is a substantially V-shaped bracket or supporting member 20, which is apertured to receive the stud 18', said stud also passing through an opening 22 in the plate 13. The dog 17

65

is positioned in the slot 18 in said stud 18', said dog being supported in said stud by the conducting plate 13 (Fig. 5). The points of said slotted stud 18' extend above the conducting plate 13 and are bent over toward each other to hold the dog in place, as shown in Fig. 5. The inner end of said dog passes through an opening 16' provided in the shell contact 16. Said dog is limited in its lateral

70

movement in one direction by the coil spring 23, having one end thereof imbedded in the lower face of said bracket as shown at 24, the other end of said spring 23 engaging a lug 25 formed integral with and extending downwardly from the dog 17.

75

The locking operation of this device is as follows: When the threaded contact or plug portion of a lamp is screwed into the threaded shell contact 16, it will engage the inner end of the dog 17, and depress the same out of the path of the threaded contact portion of the lamp against the influence of the spring 23. The latter serves to constantly press the dog against the adjacent side of the plug portion of the lamp, so that upon attempted unscrewing of the lamp, the inner end of the dog will dig into said plug portion of the lamp and prevent such unscrewing movement thereof whereby the lamp is locked in place and theft or unauthorized removal thereof is prevented.

85

It is desirous when using locking devices of the type shown herein that detachable means be provided for unlocking the device, said means being readily attachable and being designed to be carried by a person authorized to remove the lamp.

95

The preferred form of unlocking means as shown in the drawings comprises a key 105 which is formed of a rod 26 having a cov-

- ering of insulating material 27, and carrying a handle 28 on the end thereof for manipulating said key. The rod 26 is internally threaded for a short distance at 5 the end opposite the handle 28. A recess 29 is formed in the base 10 to afford a passage for the insertion of said key for engagement of the threaded end thereof with the threaded end 19 of the stud 18'.
10 With this arrangement, it is only necessary, when unlocking the device, to insert the threaded end of the key into the recess 29 and screw the same on to the threaded end 19 of the stud to the full extent of the 15 threaded engagement therewith, whereupon a continued turning of the key in the same direction will retract said dog, that is, move the same out of locking engagement with the lamp so as to permit of ready removal 20 thereof.

The dog 17, as shown in Figs. 1 and 4, is wide enough to engage two threads of the threaded plug or side contact portion of the lamp, thereby overcoming any possibility 25 of the point of the dog slipping between the threads which would result in an ineffective lock.

The threaded stem 19 of the stud 18' is provided with a left hand thread instead of the 30 more common right hand thread as generally used. This is for the reason that it would be more difficult for one who wished to steal the lamp to find a screw threaded object which could be used as a key if a left hand 35 threaded object were required than it would be if a right hand threaded object could be used. Furthermore, tools for cutting right hand threads are common in machine shops and similar places while tools for cutting left hand threads are usually not so readily 40 attainable. Consequently, the left hand thread gives a greater degree of assurance

against theft or unauthorized removal of the lamp than would the right hand thread in a device of this type. 45

Having thus described our invention, what we claim as new and desire to secure by Letters Patent of the United States is:

1. A lamp locking socket comprising a plate, a threaded shell contact mounted on said plate, a second plate mounted on said first plate and spaced therefrom, said plates having aligned bearing openings, a pivot pin mounted in said bearing openings, and a dog mounted on said pivot pin for engaging the lamp base. 50

2. A lamp locking socket comprising a plate, a threaded shell contact mounted on said plate, a second plate mounted on said first plate and spaced therefrom, said plates having aligned bearing openings therein, a pivot pin mounted in said bearing openings, and a dog mounted on said pivot pin for engaging the lamp base, said pivot pin being provided with key-engaging means, 60 whereby a key may be used to turn said pivot pin to control said dog. 65

3. A lamp locking socket comprising a plate, a threaded shell contact mounted on said plate, a second plate mounted on said first plate and spaced therefrom, said plates having aligned bearing openings, a pivot pin mounted in said bearing openings, and a dog mounted on said pivot pin for engaging the lamp base, said pivot pin having a 70 left-hand screw-threaded portion for engaging the corresponding portion of a controlling key, whereby the key may be screwed onto the end of said pivot pin to control 75 said dog. 80

In witness whereof, we have hereunto subscribed our names.

REUBEN B. BENJAMIN.
PAUL D. PHILLIPS.
